UNITED STATES PATENT OFFICE.

PHILIP YOE, OF DAYTON, OHIO, ASSIGNOR TO HIMSELF, EDWARD W. HANLEY, AND KERIEN FITZPATRICK, OF DAYTON, OHIO.

VOTING-MACHINE BOOTH.

SPECIFICATION forming part of Letters Patent No. 789,348, dated May 9, 1905.

Application filed December 27, 1904. Serial No. 238,539.

To all whom it may concern:

Be it known that I, PHILIP YOE, a citizen of the United States, residing at Dayton, in the county of Montgomery and State of Ohio, have 5 invented certain new and useful Improvements in Voting-Machine Booths; and I do declare the following to be a full, clear, and exact description of the invention, such as will enable others skilled in the art to which it applies 10 to make and use the same, reference being had to the accompanying drawings, and to the figures of reference marked thereon, which form a part of this specification.

This invention relates to new and useful improvements in voting-machine booths.

The object of the invention is to provide an election-booth which is so constructed and operated that a judge of election or other officer having charge of a voting precinct may obtain 20 serve the ballot-board after each voter leaves the booth and without moving out of his position. In other words, the ballot-board faces the election officer, and the inclosure structure is securely locked while the voter is selecting his ballot.

Preceding a detail description of the invention reference is made to the accompanying drawings, of which—

Figure 1 is an isometric perspective view 30 of the voting-booth intact. Fig. 2 is a similar view of the framework with the concealing fabrics removed. Fig. 3 is a detail horizontal plan view of the actuating mechanism for opening and closing the entrance to the booth. Fig. 4 is an enlarged detail view of the actuating mechanism, showing it in a position which closes the booth and locking the same. Fig. 5 is a similar view showing the mechanism in a position which opens the booth 40 for exit and entrance. Fig. 6 is a detail view of the weight mechanism which holds the operating-lever in its raised or lowered positions.

In a detail description of the invention similar reference characters indicate corresponding parts.

The ballot-board framework 1, which supports the voting mechanism, (not shown,) is mounted upon base-standards 9 and has jour-

naled in its opposite sides cam and lever rock- 50 shafts 10 and 11, to be again referred to. The inclosing framework for the screens or fabrics consists of upright rods or standards 22, which have their lower ends mounted in extensions 16, which are parts of the base-standards. 55 These upright rods or standards 22 extend at right angles at their upper ends and are supported in brackets 13, which are secured to the framework 1. 3, 4, and 5 are transverse bars or connections which join said rods or standards 22 at their upper and lower ends and at the middle. 7 designates a side cross-bar which is attached to the middle portion of one of the rods or standards 2 and is mounted at its other end in a bracket 15, which projects 60 from the middle portion of one of the upright sides of the framework 1: 6 is a similar rod lying parallel with the rod 7 and joining the lower end of said upright or standard and having its other end connected with a bracket 14 65 of one of the base-standards 9. The lower portion of this stationary inclosing frame has a permanent screen or fabric 18, consisting of any suitable material, which is secured to the rods or standards 22 and to the cross-bars 4 and 5 and is carried around one side of the framework and is there secured to the bars 6 and 7, thus making a permanent inclosure 70 for the lower portion of the booth. The upper screen or fabric 17 is movable from the 75 lower end, its upper end being secured to the upper horizontal portions of the rods or standards 2 and to the upper cross-bar 3. The lower edge of said screen or fabric 17 is carried around and secured to the movable inclosure-frame 8, one end of which is journaled in a socket 28 on the lower end of a crank 31, which is fixed to the rock-shaft 10, and the other end of which is journaled in a socket 28 on the lower portion of an angular lever 32, which is 80 fixed to the other end of the rock-shaft 10. The lever 32 is actuated to raise and lower the frame 8 by the following mechanism: 19 85 designates a plate which is rigidly mounted upon an end of the rock-shaft 11 and has rigidly secured to it an operating handle or crank 12, by means of which said plate 19 is rocked from and to the other extreme position. (Shown 90 95

in Figs. 4 and 5.) 20 and 21 designate studs which project from the outer face of the plate 19 in positions to ride against the cam-surfaces 27 and 24 of said lever 32 and to thus 5 actuate said lever, and therewith the rock-shaft 10 and movable inclosure-frame 8, according to the direction of movement given the operating-handle 12. It will be seen that the paths of initial movement of the studs 20 and 21 are 10 radial to the turning-point 11 of the plate 19. 23 designates a stop projecting from a side of the framework 1, which engages the upper portion of the lever 32, during which time the stud 21 on plate 19 occupies the bend of 15 the lever 32. At such time the operating-handle 12 is in its lowest position and the screen or fabric 17 incloses the upper portion of the booth. A voter is then supposed to be 20 within the booth. The weight 30, which is suspended from rock-shaft 11 by crank-arm 29, assists the mechanism in being maintained in its depressed position. When the operating-handle 12 makes about one-fifth of a revolution in its upward movement, the stud 20 25 engages the cam-surface 27 and throws said lever, and in the meantime the stud 21 rides over the lever-surfaces 24 and 25 and enters the stop portion 26 of said lever. The booth is then open for a voter to make his exit. In 30 this operation of the screen or fabric 17 the movement of the shaft 11 has reversed the position of the weight 30, and in such position said weight 30 exerts an upward pressure on the operating-handle 12. In closing the 35 booth the operating-handle 12 is lowered and the stud 21, which is in engagement with the stop end 26 of the lever, throws said lever to the other position. The operating-handle 12 is controlled by a full-stroke mechanism. 40 (Not shown, but which is the subject-matter of a separate application.) In the initial movement of elevating the handle 12 the stud 21 rides over the arc surface 24 of the lever before the inclosure-frame 8 begins its movement. 45 In other words, the movement of said frame only begins when the stud 21 reaches the surface 25 and stud 20 reaches surface 27. It will be understood that said inclosure-frame will be normally locked by the stud 21, 50 projection 26, and surface 25. This idle movement of the mechanism will be utilized in registering and returning the voting mechanism (not shown) to its normal position. This registering mechanism is the subject-matter of 55 another application for Letters Patent.

The operation is as follows: The operating-handle 12 and the inclosure-frame 8 will be in raised positions, as shown in Fig. 5. The voter operates said handle to its lowest position, which also lowers the inclosure-frame 8. 60 After voting he operates the handle 12, raising it to its limit, and leaves the booth.

Having described my invention, I claim—

1. In a voting-machine booth, a screen per- 65 manently inclosing the lower portion of the

booth with the exception of the entrance side, and an additional screen inclosing the upper portion of the booth including the entrance side, with means for elevating and lowering said upper screen to permit ingress and egress 70 to and from the booth.

2. In a voting-machine booth, a screen permanently inclosing the lower portion of the booth exclusive of the entrance side, an additional screen inclosing the upper portion of 75 the booth inclusive of the entrance side, a frame to which said upper screen is attached at its lower edge, and means for actuating said frame to raise and lower the said upper screen. 80

3. In a voting-machine booth, a screen inclosing the rear and sides of said booth, a movable frame to which the lower portion of said screen is attached, a lever to which said frame is attached and a rock-shaft to which 85 said frame and said lever are attached.

4. In a voting-machine booth, a screen inclosing the rear and the sides of said booth, a movable frame, rock-shafts to one of which said frame is attached, a lever attached to the 90 other of said rock-shafts and to which the other end of said frame is attached, and means connected to the rock-shaft with which said frame is connected for actuating said shaft and said lever, to raise or lower said screen. 95

5. In a voting-machine booth, an inclosure-frame, and an operating-lever adapted to actuate said frame, and means for locking said frame in a concealing position, said means being actuated by the operating-lever. 100

6. In a voting-machine booth, the combination with a ballot-board, a movable inclosure-frame mounted thereon, operating mechanism for said frame, and means for locking said frame until said operating mechanism is operated a predetermined distance. 105

7. In a voting-machine booth, the combination of a ballot-board, a movable inclosure-frame mounted thereon, and operating mechanism for said inclosure-frame, and means for 110 coupling said inclosure-frame and operating mechanism during the final stroke of said operating mechanism, and to compel said frame and said operating mechanism to move in unison. 115

8. In a voting-machine booth, the combination of a ballot-board, a movable inclosure-frame mounted thereon, operating mechanism for said inclosure-frame, and means for holding said operating mechanism in its fixed 120 position.

9. In a voting-machine booth, the combination of a ballot-board, a movable inclosure-frame mounted thereon, operating mechanism for said inclosure-frame, and means for holding 125 said operating mechanism in its raised and lowered positions.

10. In a voting-machine booth, a stationary inclosure-frame, a movable inclosure-frame, operating mechanism for said movable frame, 130

and means for locking said movable frame until said operating mechanism is moved a definite distance.

11. In a voting-machine booth, a stationary inclosure-frame, a movable inclosure-frame, operating mechanism for actuating said movable frame, and means for moving and coupling said operating mechanism to said movable frame so that said operating mechanism 10 and the said movable frame may move in unison in the final operation of said mechanism.

12. In a voting-machine booth, a stationary inclosure-frame, a movable inclosure-frame, operating mechanism for said movable frame, 15 and means for holding said operating mechanism in its raised position.

13. In a voting-machine booth, a stationary inclosure-frame, a movable inclosure-frame, operating mechanism for said movable frame, 20 and means for holding said operating mechanism in its raised and lowered positions.

14. In a voting-machine booth, a stationary inclosure-frame, a movable inclosure-frame, an operating - handle, means interposed between 25 said movable frame and said handle for imparting movement to said frame, and means

for locking said frame until the operating-handle is coupled with said frame.

15. In a voting-machine booth, a stationary inclosure-frame, a movable inclosure-frame, 30 an operating - handle, means interposed between said handle and said frame for imparting movement to said frame, means for locking said frame, during the initial movement of the handle, and means for coupling said 35 frame and said handle.

16. In a voting-machine booth, a stationary inclosure-frame, a movable inclosure-frame, an operating - handle, means interposed between 40 said handle and said frame for imparting movement to said frame, means for locking said frame during the initial movement of the handle, means for coupling said frame and said handle, and means for holding said 45 operating-handle in its raised position.

In testimony whereof I affix my signature in presence of two witnesses.

PHILIP YOE.
